DESIGN FOR A BEVERAGE DISPENSER

Jacob Levin, New York, N. Y.

Application August 19, 1947, Serial No. 140,947

Term of patent 14 years

(Cl. D2—3)

To all whom it may concern:

Be it known that I, Jacob Levin, a citizen of the United States residing at the city of New York, county of Bronx, State of New York, have invented a new, original, and ornamental Design for a Beverage Dispenser, of which the following is a specification, reference being had to the accompanying drawing, forming part thereof.

The figure is a front perspective view of a beverage dispenser, showing my new design.

I claim:

The ornamental design for a beverage dispenser, as shown and described.

JACOB LEVIN.
